UNITED STATES PATENT OFFICE.

HAMILTON E. SMITH, OF NEW YORK, N. Y.

CLOTHES-SUPPORTING APRON FOR IRONING-MACHINES.

SPECIFICATION forming part of Letters Patent No. 228,565, dated June 8, 1880.

Application filed November 7, 1879.

To all whom it may concern:

Be it known that I, HAMILTON E. SMITH, of the city, county, and State of New York, have invented a new and useful Improvement 5 in Clothes-Supporting Aprons for Ironing-Machines, which improvement is fully set forth in the following specification, reference being had to the accompanying drawings, in which—

10 Figure 1 represents a longitudinal section of an apron embodying my invention. Fig. 2 is a plan or top view thereof. Fig. 3 is a transverse section of the same. Fig. 4 shows a modification.

15 Similar letters indicate corresponding parts.

My invention relates to aprons for supporting or carrying the clothes around the cylinder in ironing-machines; and it consists in an apron constructed of a flexible back combined with 20 transverse fibrous or textile face-sections, and rigid shoes for sustaining the face-sections upon the back so that the apron obtains a soft or yielding surface and remains spread or extended in breadth without losing its 25 flexibility.

Another feature is to make the shoes with a dovetailed cross-section, in order to retain the face-sections therein and to increase the flexibility of the apron, as hereinafter more 30 fully set forth.

In the drawings, the letter A designates the back; B, the face-sections, and C the shoes.

I make the back A of woven fabric or of 35 leather or other flexible material, and in this example it is divided into three sections, which are joined by the shoes C.

The face-sections B constitute the top or working surface of the apron, and consist of 40 elongated blocks of felt or other fibrous or textile fabric of, say, three-fourths of an inch in width, while they extend side by side transversely to the apron, in which position they are held by the shoes C. The shoes C grasp

45 the face-sections B, and I make the same of sheet metal or like rigid material, while I fasten them in the proper position upon the back A by rivets d or other suitable means.

The face-sections B impart to the apron a 50 soft or yielding surface, and by the shoes C these face-sections, as well as the back A, are kept stretched transversely to the apron, so

that the latter remains spread or extended in breadth, while at the same time, owing to the comparatively narrow width and the arrangement of the shoes, the flexibility of the apron is not thereby impaired. 55

I bend the sides of the shoes C inward, thereby giving the same a dovetailed shape in cross-section, as shown. One advantage 60 gained by thus shaping the shoes is that the face-sections B are retained therein without the aid of any extraneous fastenings; and another advantage is that a diverging space is created between the shoes, which allows the 65 latter to lie or fold upon each other as the apron is bent in passing around the cylinder of an ironing-machine, thereby adding to the flexibility of the apron. As the apron passes around the cylinder those portions of the 70 face-sections B which are above the shoe C are compressed upon each other, thus forming a surface which is practically continuous and solid.

In some cases I join the shoes C by means 75 of double-pointed tacks or links e, Fig. 4, passing through the back A, with the view to prevent the latter from stretching between the shoes.

If desired the back can be made of sheet 80 metal or other rigid material, with hinge-joints between the shoes, so as to render it flexible.

What I claim as new, and desire to secure 85 by Letters Patent, is—

1. An apron for ironing-machines, consisting of a flexible back combined with fibrous or textile face-sections, and rigid shoes for sustaining the face-sections upon the back, substantially as and for the purpose described. 90

2. An apron for ironing-machines, consisting of a flexible back combined with fibrous or textile face-sections, and rigid shoes having a dovetailed cross-section for sustaining the face-sections upon the back, substantially as 95 and for the purpose described.

In testimony that I claim the foregoing I have hereunto set my hand and seal this 5th day of November, 1879.

HAMILTON E. SMITH. [L. S.]
